UNITED STATES PATENT OFFICE.

HANNAH GREEN GAUNT, OF VICTORIA, BRITISH COLUMBIA, CANADA.

STOVE-FLUE-CLEANING DEVICE.

Application filed April 1, 1924, Serial No. 703,552, and in Canada September 18, 1923.

This invention relates to devices for cleaning the flues of domestic cooking stoves, particularly where soft coal is used for fuel and soot is rapidly formed and deposited 5 within and around the walls of the flues; such flue cleaning is usually performed by a simple scraper, but with flue scrapers as ordinarily used much nuisance is caused owing to the fine and feathery particles of 10 soot escaping into the room, but with my invention which consists of a scraper in combination with a special mop-like appliance the fine soot is collected by the device and prevented from escaping into the 15 apartment.

In the drawings herewith Fig. 1 shows a front view, Fig. 2 a side view, and Fig. 3 an end view of my device. *a* is a stout wire handle of convenient length and form, 20 secured to a folded flat plate clip *b*, within the folds of which are securely clamped and held a flat or nearly flat series of fibre strands *c* forming a fringe to one of the scraper edges, somewhat after the fashion 25 of a mop, this fibre fringe is conveniently made from binder twine.

The simplest method of making such a device as shown in the drawing is to take a rectangular piece of fairly stiff iron or steel 30 plate and fold the same equally about its longer centre line, pierce the double plate for the rivet in the position shown, lay the fibrous strands between the fold taking care that the strands pass on the inner side of the 35 rivet, the head extremity of the handle is formed into a loop through which the rivet

is passed, and the three portions firmly riveted together, the portion of the scraper head at the fold being flattened to provide a scraper edge.

The method of using the device is to immerse the working end in a pail of water and after shaking off the surplus to pass the scraper-mop along and about the stove flues, when the fine particles of soot and especially the filament of soot which usually give the most trouble will readily adhere to the moistened fibre strands and are then easily disposed of by a rapid rinse in the pail of water; this process is repeated a few times 50 depending on the state of the flues and the latter are left in excellent condition for a clear draught, the process having created little or no nuisance in the way of dust or soot; the opposite edge of the scraper device is used in the ordinary way in case there should be any pieces of soot adhering to the flue that are not removed by the previous process.

What I claim as my invention and desire to secure by Letters Patent, is:

A flue cleaning device comprising a head formed of a metal plate folded over in U-shaped fashion, a fringe of fibrous strands securely clamped between the opposed walls 65 of said head, the portion of the head at the fold being flattened to provide a scraper edge, and a handle connected to a side wall of said head and extending substantially perpendicularly therefrom.

HANNAH G. GAUNT.
